CLAIM

The ornamental design for a bag, as shown and described.

DESCRIPTION

FIG. 1 is a top, front, right perspective view of a bag showing our new design;

FIG. 2 is a top, front, right perspective view of an alternative claimed configuration of a bag thereof;

FIG. 3 is a top, front, right perspective view of an alternative claimed configuration of a bag thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines illustrated on the claimed shaded surfaces of the bag represent stitching and form part of the claimed design. The remaining broken lines illustrate portions of the bag and form no part of the claimed design.
